DESIGN FOR A GLOVE

Julius A. Higier, Johnstown, N. Y.

Application May 28, 1937, Serial No. 69,591

Term of patent 3½ years

To all whom it may concern:

Be it known that I, Julius A. Higier, a citizen of the United States of America, residing in Johnstown, county of Fulton, and State of New York, have invented a new, original, and ornamental Design for a Glove, of which the following is a specification, reference being had to the accompanying drawing, forming part thereof, wherein,

The characteristic feature of my design resides in the squared arrangement of the fingertip portions of the glove, in combination with a contrasting inner insert on the top and sides of the finger portions, as shown.

I claim:

The ornamental design for a glove, substantially as shown, and described.

JULIUS A. HIGIER.
